(57) **CLAIM**

The ornamental design for a light fixture, as shown and described.

DESCRIPTION

This application is related to commonly assigned, concurrently filed application Ser. No. 29/269,131, the disclosure of which is hereby incorporated by reference herein.

FIG. 1 is an isometric view of the light fixture of the present invention;

FIG. 2 is a top plan view thereof;

FIG. 3 is a right-side elevation view thereof, the left-side elevation view being a mirror image thereof;

FIG. 4 is a front elevation view thereof; and,

FIG. 5 is a bottom plan view thereof.

The broken line showing is for illustrative purposes only and forms no part of the claimed invention.
